UNITED STATES PATENT OFFICE.

JOHN ALLES, OF EXETER, CALIFORNIA, ASSIGNOR OF ONE-HALF TO ABRAHAM DINKINS, OF WOODLAKE, CALIFORNIA.

CONTROLLING DEVICE FOR ELECTRIC CIRCUITS.

1,412,591.

Specification of Letters Patent. Patented Apr. 11, 1922.

Application filed April 5, 1919. Serial No. 287,661.

To all whom it may concern:

Be it known that I, JOHN ALLES, a citizen of the United States, residing at Exeter, in the county of Tulare, State of California, have invented certain new and useful Improvements in Controlling Devices for Electric Circuits; and I do declare the following to be a full, clear, and exact description of the same, reference being had to the accompanying drawings, and to the characters of reference marked thereon, which form a part of this application.

This invention relates to improvements in pneumatically and mechanically actuated mechanism for throwing the switch of an electric pump motor under certain conditions to stop the pump, the same being particularly designed and adapted to be used in connection with centrifugal pumps used in connection with pumping water for irrigating purposes.

The conditions of the flow of water in which these pumps operate are such that very often the capacity of the pump exceeds the inflow of water into the sump, etc., in which the pump is positioned. In such cases the load is taken off the pump and motor, which runs at abnormal speed.

The principal object of my invention therefore is to provide a means for automatically shutting off the current which feeds the motor and thus stopping the pump, the instant the pump begins to "suck air" and a vacuum is formed therein.

I have also provided a signal means operable in connection with the motor circuit breaking means whereby the operator in the ranch house or elsewhere will be immediately notified of the stoppage of the pump.

A further object is to provide a simple and inexpensive device, and yet one which will be exceedingly effective for the purposes for which it is designed.

These objects I accomplish by means of such structure and relative arrangement of parts as will fully appear by a perusal of the following specification and claims.

On the drawings similar characters of reference indicate corresponding parts in the several views.

Fig. 1 is a side elevation of a knife switch, showing my improved throwing means attached thereto, the switch being closed.

Fig. 2 is a similar view showing the main switch thrown out and the circuit broken.

Fig. 3 is a sectional view through the

vacuum diaphragm chamber, showing the coacting parts.

Fig. 4 is an elevation of the signal switch and coacting parts as used in connection with my device.

Fig. 5 is a fragmentary section transversely of the switch board, and showing the spring controlled throwing bar.

Referring now more particularly to the characters of reference on the drawing, numeral 1 indicates a switch-board of any suitable non-conducting material, on one side of which is mounted a knife switch 2, having any desired number of blades, and adapted to engage with the starting-position forks 3 and the running-position forks 4.

Slidably mounted on rods 5, secured to the base 1 is a bar 6 of suitable non-conducting material, which bar passes under the switch 2 transversely of the same and adjacent the forks 4.

Compression springs on the rods 5 normally maintain the position of the bar 6 above the top of the forks 4.

Rigidly attached to the bar 6 and slideable through the board 1 and projecting therethrough are rods 8 to the lower end of which is secured a bar 9 extending parallel to the bar 6. This bar 9 is adapted to bear against the under side of the board 1 when the bar 6 is at its highest position on the rods 5. Depending from the bar 9 centrally thereof is a bar 10 to which is secured a knife switch blade 11 adapted to contact with forks 12 of a switch 13 when the bar 6 is in its uppermost position, as indicated in Fig. 2, which permits a flow of current from a wire 14, through a switch blade 15 always preferably thrown in, thence through a wire 16 and through the blade 11 to a wire 17, thus completing a circuit in which a red lamp, or a bell, may be interposed to give an alarm.

On the under side of the board 1 opposite from the switch 13 is a bar 18 having arms 19 and 20 depending therefrom. To the bar 19 is pivoted as at 21 an arm 22 having a transverse pin 23 near one end thereof adapted to ride in a recess 24 provided in the bar 10 when the same is in its lowermost position 105 as shown in Fig. 1.

The other end of the arm 22 terminates in a narrow portion 25 adapted to rest on a roller 26 projecting from a short lever arm or trigger 27 pivoted as at 28 to the arm 20, 110

the arm 27 being pivoted and positioned at right angles to the arm 22. The end of the arm 27 opposite the roller 26 narrows down as at 27^a and projects in the groove of a collar 5 29 secured to a rod 30 projecting into a circular casing 31 and being there secured to a diaphragm 32 mounted in the casing.

The rod 30 is held in vertical position relative to the casing 31 by means of a rod 33 10 mounted to the casing and having a bearing plate 34 thereon which projects beyond the rod 30 and through which the latter slides.

The diaphragm is normally held against the upper side of the casing by counter balancing springs 35 interposed about the rod 30 15 between the casing and the plate 34, these springs being spaced by a rigid collar 30^a.

A pipe 36 is connected to the casing 31 below the diaphragm and leads to a point adjacent 20 the outlet of a centrifugal pump, not shown.

An air vent 31^a is placed in the casing 1 above the diaphragm.

A spring controlled bar 37 is mounted to 25 the plate 1 adjacent the starting-position forks 3, which bar bears against the switch blades 2 when the same is in contact with the forks 3 and makes it easier to throw the switch 2 out of contact with the said forks 30 and over to the running-position forks.

The operation of the device is as follows:—

Suppose the pump to be in operation and that the switch 2 is closed as shown in Fig. 1. 35 With the pipe 36 connected to the discharge end of the pump, there will be a pressure on the under side of the diaphragm 32 greater than atmospheric pressure when the pump delivers water. This pressure will overbalance 40 the pressure of the spring 35 and the atmosphere on top of the diaphragm, but when the sump runs dry and the pump sucks air at its inlet, the pressure on the under side of the diaphragm will be decreased sufficiently 45 to allow the atmospheric pressure thereabove to depress the diaphragm in the casing 31. This pulls down the rod 30, which causes the trigger 27 to tilt and moves the roller out from under the arm 22. The bar 50 6 is held down against the tension of the spring 7 by reason of the pin 23 in the arm 22 resting in the recess 24 in the bar 10. As soon as the end 25 of the arm 22 is released, therefore, the springs 7 acting on the bar 6 55 and the parts secured thereto, cause the said bar to move upwards, forcing the switch blades 2 out of contact with the forks 4. This, of course, breaks the circuit through the pump-motor wiring, and the same stops 60 before harm is done.

At the same time, the switch blade 11 contacts with the forks 12 of the switch 13, thus closing a lamp lighting or bell ringing circuit, as previously explained. When it is desired 65 to again start the pump, the vacuum

therein having been eliminated and the diaphragm again assumed its normal position, the switch member 2 after first being placed in contact with the starting-position forks 3, is thrown over to press down on the bar 6, 70 compressing the spring 7 thereunder, forcing the bar 9 down also. The edge of the arm 22 is positioned to bear against the under side of the bar 9 so that it is also levered into position, until by the time the switch 2 is 75 fully thrown in, the arm 22 has snapped past the roller 26 and is resting thereon, and the pin 23 in the arm 22 is seated in the recess 24. In this position, the springs 7 are held from upward action against the bar 6 and 80 will be so held until a lack of water in the pump again actuates the diaphragm.

While in this description I have designated the "upper" and "lower" sides of the board 1 and parts relative thereto, it is to be understood that such terms are only relative to the showing thereof on the drawings, as the device may be set in any desired position without impairing the operativeness thereof.

Also, while I have made especial mention 90 of an electric pump-motor, it will be evident that the same device may apply to a gasoline engine running such a pump, in which case the throwing out of the switch would break the ignition circuit of the engine, which 95 would then stop.

The motor switch may be of the oil type, and the diaphragm may be connected to actuate an auto-starter for a motor if desired.

The device is shown when the diaphragm 100 is connected to a pump with a check valve in the discharge. If the pump has a check valve in the suction pipe, the diaphragm is connected to the suction pipe and the same is drawn in when the pump is working, but 105 when the flow of water is stopped, the normal vacuum is lost and the diaphragm then springs out to throw the switch, the same being properly connected to the diaphragm stem to accomplish this.

From the foregoing description it will be readily seen that I have produced such a device as substantially fulfills the object of the invention as set forth herein.

While this specification sets forth in detail 115 the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:—

1. An electric switch including a pivoted blade adapted to close a circuit, a spring-pressed bar under the blade and bearing against the same to normally hold the blade in a circuit breaking position, and means connected to said bar for holding the same away from the blade to allow the latter to be moved 125 130

to close the circuit, said means being adapted to be automatically tripped to release and throw the blade while allowing the latter to be manually actuated at will.

5 2. An electric switch including a movable blade adapted to close a circuit, a spring actuated member pressing against the blade to normally hold the same in an open circuit position, a pivoted trip arm engaging the 10 member at one end and means engaging the trip arm at the other end for holding the member away from the blade to allow the switch to be closed, such means comprising a trigger pivoted intermediate its ends at right 15 angles to the arm and adjacent the free end

thereof and a roller projecting from the trigger and adapted to support said end of the arm when the switch blade spring actuated member is free of the blade, said end of the arm being relatively thin and the trigger 20 being adapted to be automatically rocked to throw the roller out of the path of movement of the arm to allow the latter to trip.

In testimony whereof I affix my signature in presence of two witnesses.

JOHN ALLES.
